UNITED STATES PATENT OFFICE

DONALD B. WILLIAMSON, OF PITTSBURGH, PENNSYLVANIA, ASSIGNOR TO THE PEOPLES NATURAL GAS COMPANY, A CORPORATION OF PENNSYLVANIA

WATER HEATER

Application filed July 30, 1932. Serial No. 626,460.

This invention relates to a water heater of the side arm type. That is to a water heater comprising both a storage tank and a heater proper, which latter is in return communication with the storage tank.

The specific type of water heater to which the improvements of my invention are applied has a cold water inlet to the tank in the upper region thereof; a warm water outlet 10 from the lower region of the tank to the heater coil; and a return line from the discharge end of the heater coil to the tank, this return line extending a substantial distance downwardly 15 from the top of the tank into the interior of the tank. The line from the discharge end of the heating coil is branched; one branch being the return line to the tank, and the other branch being a service line leading to 20 a hot water faucet or faucets. A check valve is interposed in the return line from the heating coil to the tank, so that the circulation of water directly to service from the tank, or a reverse flow to the discharge end of the heating coil, is prevented. Previously in a heater 25 of such type a control thermostat for the gas line to the heating coil has been positioned within the tank, and in the lower region thereof.

30 This type of heater, as definitely described above is prompt in its action, and is reasonably efficient. It carries, however, an unduly high tank temperature; and the hottest region of the tank being the upper region thereof, there is a substantial loss of heat by radiation. A defect in operation is that a considerable quantity of cold water must enter 35 the tank before the thermostat operates to supply gas to the burner of the heating coil. 40 Conversely, the temperature in the upper region of the tank reaches the high temperature noted, before the thermostat, being regulated to the lower region temperature, operates to cut off gas supply to the burner.

45 The primary object of this invention is to improve a water heater of the described type by so positioning and associating the control thermostat that it acts instantaneously to supply gas to the burner of the heating coil upon service withdrawal of water, and that it acts

under the influence of the highest tank temperature to cut off gas supply at times when no withdrawal is being made.

A further object of the invention is to provide means guarding against objectionably 55 high temperature of service water in large capacity installations.

In the accompanying drawings Figure I is an elevational view, showing a heater embodying the primary improvements of my invention; Figure II is a fragmentary elevational view, showing a modified positioning of the control thermostat; Figure III is a fragmentary elevational view showing the use of a thermostat for controlling the temperature of water flowing to service, and adaptable for addition to either structure illustrated in Figures I and II, and Figure IV is a detail view, in vertical section, showing the check valve comprised in the apparatus 60 and the fitting in which it is installed.

In the drawings reference numeral 1 designates the storage tank of the heater, which has a cold water supply pipe 2 connected at the top of the tank. A warm water outlet 75 pipe 3 leads from the bottom of the tank to a heater proper 4, which is to be understood as comprising a heating coil, or its equivalent heating element, to the intake end of which pipe 3 connects. The heater proper also 80 comprises a burner of known sort, a portion of which is shown at 5. The heater 4 has the outlet of its heating element connected to a discharge pipe 6.

Discharge pipe 6 branches; one branch 7 85 extending downwardly in tank 1 to a point adjacent the bottom thereof, and the other, or service, branch 8 leading to a faucet or faucets (not shown). Suitable means, such as a check valve 9, disposed desirably in the fitting at which the heater discharge pipe 6 branches, permits flow from pipe 6 into branch 7, but prevents substantial reverse flow through branch 7 into either pipe 6 or service branch 8.

At times when there is no withdrawal of water the circulation is therefore from the bottom of tank 1 to the heater, through the heater 4, and again to a point adjacent the bottom of the tank by way of pipe 6 and 100

branch 7. At times of service withdrawal circulation is from the bottom of tank 1, through the heater 4, and from the heater, by way of pipe 6 and service branch 7, to service. All service water is taken directly from the heater.

The gas supply line 10 has therein a pilot burner 11, and thereafter enters heater burner 5 to supply fuel thereto. The automatic 10 gas control means act to control gas flow in the region between pilot burner 11 and the main burner 5.

Fuel supply to burner 5 is controlled by a suitable valve 12, operated by thermostat 13. 15 As shown in Figure I of the drawings, thermostat 13 is mounted in a fitting 14 of cold water supply pipe 2, and comprises a bulb extending downwardly into the tank from the top thereof.

20 It is to be understood that communication is at all times open between cold water supply pipe 2 and the interior of tank 1; and also that the conditions in pipe 2, and the system with which it is connected are such, that there 25 may be reverse flow from the tank into the cold water supply pipe under the influence of high pressure conditions within the tank.

Under the conditions described for times at which there is no withdrawal of water 30 from the system, hot water from the heater enters the tank in its lower region and moves upwardly through overlying water to the upper region of the tank. This current tends to produce an equalization in the temperature of tank water, but inevitably during 35 the continuance of these conditions the upper region of the tank becomes the most highly heated region. The cycle continues until the water temperature in the upper 40 region of the tank becomes elevated to the point at which thermostat 13 has been set to operate in cutting off fuel supply to the burner.

45 By exposing the control thermostat to the highest normal tank temperature, the tank temperature is definitely limited for all regions thereof. When a chilling below thermostat setting has been produced in the upper region of the tank, the thermostat operates to again supply fuel to the heater burner. 50 Hot water then passing from the heater to the tank does not affect the thermostat until it has risen from a point adjacent the bottom of the tank to the upper portion thereof in 55 the region of the thermostat.

A service withdrawal of water from the system instantly causes cold water to enter at the top of the tank from supply pipe 2. This cold water, acting on thermostat 13, 60 operates gas valve 12 to supply fuel to burner 5. Substantially all the water passing to service from the bottom of tank 1, and through heater 4, is directly heated during 65 its passage through the heater. A very 65 slight initial withdrawal of water suffices to

supply fuel to the heater burner, and thereby causes all succeeding water to be highly heated in passing to service.

As thus subjected to inflowing cold water, 70 the thermostat is caused to act much more promptly than if subjected only to tank temperature, and the promptness of thermostat action is even more marked in comparison with a system in which the thermostat acts under the temperature influence of water in 75 a lower region of the tank.

In the modification shown in Figure II of the drawings, the thermostat has a highly specialized mounting in the extreme upper 80 region of tank temperature influence. In this modification cold water supply pipe 2 is provided with a horizontal extension 15 in which the bulb of thermostat 13 lies. A fitting 16 gives access to the interior of tank 1 at the upper extremity thereof.

85 In normal operation of the system, that is when no withdrawal is made, water at the highest permitted tank temperature rises through fitting 16, and surrounds the bulb of thermostat 13 lying in extension 15 of cold water supply pipe 2. The slightest disturbance of this condition, as caused by faucet opening or even by a slight contraction of water within the tank, affects the 90 thermostat and causes it to open the gas supply valve 12. When once operated to supply fuel to the burner, thermostat 13, as thus positioned, does not act to close the fuel supply valve until tank water has reached a 95 temperature so elevated that expansion of the water in the tank causes hot water to again enter extension 15 in such manner that the thermostat is subjected wholly to its influence.

100 Advantages of my improved water heater are the instantaneous delivery of hot water at the faucet, and the continued delivery of a relatively great volume of water without appreciable drop in faucet temperature. 105 There is further the advantage, based on the manner in which the control thermostat is influenced, of maintaining a lower average tank temperature at all times, and economizing in fuel consumption by lessening radiation loss in the upper region of the tank. 110 My water heater, to the fullest extent yet realized, combines the advantages of an instantaneous water heater with the advantages 115 of a tank type water heater.

120 As a specific example, my water heater, when constructed with a 15 gallon tank and a 25,000 B. t. u. coil, delivers water at a temperature above 110° Fahrenheit for an indefinite time. Extremely low rates of flow produce rather high, but not dangerous, faucet temperatures, and the faucet temperature 125 may be easily reduced by increasing the volume of flow. The feature of faucet temperature control is governed by heating coil capacity, tank temperature (thermostatic 130

control at the tank), and as a controllable element, the rate of flow.

I have found that my water heater in very large installations is not adequately under 5 faucet control in determining the upper limit of faucet temperature. In installations, therefore, which approximate or exceed a tank capacity 60 gallons and a 45,000 B. t. u. coil I prefer to add automatic means for 10 limiting positively faucet temperature.

Figure III of the drawings illustrates the use of an independent thermostat to definitely limit the temperature of the water in the service branch pipe 8. In such modification 15 the loop of gas line 10 lying between pilot burner 11 and main burner 5 is greatly extended, as for a yard or more, along service branch 8. This extended portion of gas line 10 has therein a valve 17, which is under the 20 control of a thermostat 18 in the pipe 8.

This thermostat 18 controls only the temperature of service water to the faucet to cut off the gas supply to the burner when a predetermined temperature for service 25 water has been exceeded.

The two thermostats 13 and 18 do not act in a differential manner, and do not either of them interfere with the action of the other; one acting to control tank temperature, and the other acting to control service water temperature which is materially higher than tank temperature. When its action in cutting off gas supply has lowered the 30 temperature of the water in pipe 8 to the point of safety, thermostat 18 gradually opens valve 17, and restores complete control of the system to thermostat 13. As explained 35 thermostat 13 closes its associated valve 12 only at such time as cessation of water withdrawal has permitted tank temperature to be again built up to the normal carrying point.

I claim as my invention:

1. In a water heater having a circulation system comprising a storage tank, a heating 45 element, a cold water line entering at the upper end of the storage tank, an outflow line at the lower end of the storage tank leading to the inlet end of the heating element, a branched discharge pipe from the outlet end 50 of the heating element having one branch thereof leading to service and another branch thereof discharging intermediate the height of the tank and having therein means preventing substantial return flow through that 55 branch to the heating element or to service; the combination of a burner for the heating element, a gas supply line to said burner, and a control thermostat subjected by its position of mounting to the direct chilling effect of the 60 cold water line to the tank upon and during service withdrawals of water from the circulating system and subjected to the effect of tank water temperature in the extreme upper region of the tank in periods between service 65 vice withdrawals of water.

2. The combination of the next preceding claim in which the thermostat is mounted in an extension of the cold water supply line in a position wholly outside the storage tank, and in which by a connection from the extreme upper region of the tank to the extension of the cold water supply line in which the thermostat is mounted the thermostat is subjected to tank water temperature in the extreme upper region of the tank during periods between service withdrawals of water. 75

3. In a water heater having a circulation system comprising a storage tank, a heating element, a cold water line entering at the upper end of the storage tank, an outflow line 80 at the lower end of the storage tank leading to the inlet end of the heating element, a branched discharge pipe from the outlet end of the heating element having one branch thereof leading to service and another branch thereof discharging intermediate the height of the tank and having therein means preventing substantial return flow through that branch to the heating element or to service; the combination of a burner for the heating element, a gas supply line to said burner, a main control thermostat subjected by its position of mounting to the direct chilling effect of the cold water supply line to the tank upon service withdrawals of water from the circulating system and subjected to the effect of tank water temperature in the extreme upper region of the tank in periods between service withdrawals of water, and a thermostat disposed in the service branch pipe from the heating element to service and acting independently of the main control thermostat during service withdrawals of water to impose an upper limit of temperature on water passing from the heating element to service. 95

4. The combination of the next preceding claim in which the main control thermostat is mounted in an extension of the cold water supply line in a position wholly outside the storage tank, and in which by a connection from the extreme upper region of the tank to the extension of the cold water supply line in which the main control thermostat is mounted the thermostat is subjected to tank water temperature in the extreme upper region of the tank during periods between service withdrawals of water. 100

In testimony whereof I have hereunto set my hand.

DONALD B. WILLIAMSON.
